(57) **CLAIM**

The ornamental design for a window display for a toolbox, as shown and described.

DESCRIPTION

FIG. 1 is a perspective view of a window display for a toolbox used with a tool box, showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and,
FIG. 7 is a bottom plan view thereof.

The broken line showing, in the views, is for illustrative purposes only and forms no part of the claimed design.
